UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,242,008.

Specification of Letters Patent.

Patented Oct. 2, 1917.

Application filed May 25, 1916. Serial No. 99,748.

To all whom it may concern:

Be it known that I, ALBEN E. LUNDELL, a citizen of the United States, residing at New York, in the county of Bronx and 5 State of New York, have invented certain new and useful Improvements in Telephone-Exchange Systems, of which the following is a full, clear, concise, and exact description.

This invention relates to telephone exchange systems and more particularly to the 10 supervision of connections in telephone exchanges.

In telephone systems in which connections are established through a plurality of offices, 15 it was found desirable, for the purpose of saving current, to provide so-called "dry" trunks between offices, *i. e.*, trunks through which no supervisory current flows during conversation. Current flows through the 20 "dry" trunks only during the setting up and the severing of the connection. The supervisory means, *e. g.*, a relay provided in the incoming circuit, is responsive to this current and in turn controls a supervisory signal at a connecting operator's position.

In order to prevent the untimely actuation of the supervisory means in systems of this type, it is the object of the present invention to delay the actuation of the supervisory means during the establishment of the connection for a sufficient time to permit 30 an attendant to complete the establishment of a call, whereupon the current source will be disconnected from the trunk until the 35 severing of the connection.

In the drawings, Figures 1 and 2, placed side by side, represent the circuit arrangement of a semi-automatic telephone exchange system, only so much being shown of the 40 circuits and apparatus as is necessary for a clear understanding of the present invention.

A connecting operator, whose position is indicated in Fig. 1, extends an incoming line 45 to a B operator's position located at a second office (shown in Fig. 2 to the left of the dotted line) by operating selector switches 10 and 11 under the control of her sender. The sender and the selector switches are only 50 schematically shown in the drawings. Preferably, the sender, the selector switches and the associated controlling apparatus described in my Patent No. 1,168,319 of January 18, 1916, are used in this system. By 55 means of her sender, the connecting operator

actuates also an indicating device 100 at the B operator's position for informing this operator of the number of the desired subscriber. The indicators 101, 102, 103 and 104 are of the well-known sequence switch 60 type described in the above mentioned patent, and may control, in their actuated positions, any well-known visual or audible signals. The B operator confers through a call circuit 105 with a C operator located at a 65 third exchange (shown in Fig. 2 to the right of the dotted line), and this operator establishes the connection with the called line. The trunk extending from a jack 136 at the B operator's position to a repeating coil 144 70 at the C operator's position is a "dry" trunk.

A clear understanding of the invention may be had from the following detailed description and the appended claims.

A calling subscriber at substation 12 desiring to obtain connection with a subscriber located at station 110 removes his receiver from the switchhook, causing thereby the display of a well-known calling signal 13 in front of the connecting operator, who inserts a plug 14 into an answering jack 15 of the substation 12, establishing a circuit from ground through the winding of a relay 16, the sleeve contacts of plug 14 and jack 15, and the winding of a cut-off relay 17, to 80 a grounded battery. Relay 17 causes the extinguishing of signal 13, and relay 16 closes a circuit from ground, through its armature and front contact, a contact 18, and the power magnet of a sequence switch 19 to 85 a grounded battery. Under the control of a normal spring 20, this sequence switch is moved into position 11.

The connecting operator converses in the well-known manner with the calling subscriber and then sets up on her keyboard (not shown) the number of a second office and also the number of the called subscriber. In positions 2 and 4 of a sequence switch associated with the sender, the selectors 10 and 100 11 are under control of said sender. After selector 11 has seized the desired trunk conductors 21 and 22, leading to the B operator's position located at the second office, the sender sequence switch will be in position 8. A circuit is thus established from ground, through a contact 111 of a sequence switch 112, conductor 22, the lower brushes of selectors 11 and 10, a contact 23 of sequence switch 19, a contact 24 of the sender 110

sequence switch, the armature and back contact of the "zero" counting relay 25 associated with the sender, the winding of a sender stepping relay 26, contact 27 of sequence switch 19, the upper brushes of selectors 10 and 11, trunk conductor 21, contact 113 of sequence switch 112, and the winding of a stepping magnet 114 associated with the indicating device 100, to grounded battery. This magnet 114 is adapted to move arm 115 of the indicating device upon its deenergization. The magnet 114 establishes, upon its energization, a circuit from ground, through its armature and front contact, arm 115, and the power magnet of the indicator 101 to grounded battery. Indicator 101 is thus set in motion and closes upon each step, a contact 120, thus causing the connection of a ground to the above traced fundamental circuit for short-circuiting the stepping magnet 26 of the sender a desired number of times. A more complete disclosure of the indicator arrangement may be had from my application Serial No. 121,565, filed September 22, 1916. As well known, under the control of the stepping relay 26, the counting relays are successively operated, and when the last or "zero" counting relay 25 becomes actuated, it opens the fundamental circuit at its back contact, causes the deenergization of stepping magnet 114 of the indicating device and the stepping of the sender sequence switch into position 10. Upon the deenergization of magnet 114, arm 115 connects in circuit indicator 102, and the operation of this indicator and the other indicators is controlled in the same manner as described in connection with indicator 101, for causing the display of the called subscriber's designation, at the B operator's position. Indicators 101, 102 and 103 control at their contacts 121, 122 and 123, respectively, the operation of stepping magnet 26.

Upon the displacement of indicator 104 from its normal position, a contact 124 is closed, and when the stepping magnet 114 becomes deenergized upon the moving of the sender sequence switch out of its 14th position, a circuit is established from ground, through the armature and back contact of magnet 114, contact 124, a contact 125 and the power magnet of sequence switch 112 to grounded battery, for moving this sequence switch under the control of its normal spring 125 out of position 1 and into position 4.

The sender sequence switch is moved from position 14 to 16, and thus, after the setting of the indicating device 100, a circuit is established from ground through sender-sequence switch contact 30, a contact 31 and the power magnet of sequence switch 19 to grounded battery, for moving sequence switch 19 into position 14. In this posi-

tion of sequence switch 19, a lamp 32 is lighted, indicating to the connecting operator that the B operator has been reached and informed of the number of the called subscriber. There is another lamp 33 provided at the position of the connecting operator which indicates that disconnection is desired. This lamp may be lighted in position 16 of sequence switch 19, when a supervisory relay 34 is deenergized. In order to prevent the giving of a false disconnecting signal to the connecting operator, the moving of sequence switch 19 into position 16 must be delayed until this supervisory relay 34 is energized and means must be provided for permitting the C operator to complete the connection to the called subscriber's station. This is accomplished in the following manner.

When sequence switch 112 reached position 4, a circuit was closed from grounded battery, through the winding of a relay 130, contact 131 of sequence switch 112, trunk conductor 21, the upper brushes of selectors 11 and 10, contact 35 of sequence switch 19, and a secondary winding of a repeating coil 36, to ground. Relay 130 closes a circuit from ground, through its armature and front contact, contact 132, and the power magnet of sequence switch 112 to grounded battery, for moving this sequence switch into position 7. The B operator depresses now a call circuit button 133, thus connecting her head set 134 through the call circuit 105 to a head set 135 of the C operator. The B operator informs the C operator of the number of the desired subscriber, and receives also instructions from the C operator as to which trunk to use.

Supposing that the instruction was to use the trunk terminating in a jack 136 in front of the B operator, this operator inserts plug 137 into this jack, establishing thus a circuit from grounded battery, through the winding of a relay 138, the sleeve contacts of plug 137 and jack 136, and a resistance 139 to ground. Relay 138 closes a circuit from ground, through its armature and front contact, a contact 140 and the power magnet of sequence switch 112 to grounded battery, for moving this sequence switch into position 9. A further circuit is established from the positive pole of battery, through the lower winding of a relay 141, a contact 142 of a relay 143, a primary winding of a repeating coil 144, the ring contacts of jack 136 and plug 137, the winding of a relay 145, the tip contacts of plug 137 and jack 136, a primary winding of repeating coil 144, a contact 146 of relay 143 and the upper winding of relay 141 to the negative pole of battery. Relay 141 closes a circuit from ground, through its armature and front contact, the winding of a relay 150, the lower back contact and armature of a relay 151, and a lamp 152 to 130

grounded battery. Relay 150 becomes energized and lamp 152 is lighted, indicating to the C operator that the B operator has performed her duty. Relay 150 closes a circuit for relay 143, which opens at its contacts 142 and 146 the circuit of relay 145, but establishes, through its contact 153 and a resistance 154, a local energizing circuit for relay 141. Relay 145 being deenergized, the moving of sequence switch 112 into position 17 must be delayed in order to give the C operator sufficient time to insert a plug 154 into a jack 155 in which the called subscriber's line terminates.

15 Commutator segments 157 and 158 are mounted on a constantly rotating shaft 156 in such a manner that the conducting segment of plate 157 contacts with its brush about two seconds ahead of the conducting segment of plate 158. Plate 157 closes, through contact 160, a driving circuit for sequence switch 112 and moves it into position 10. During the time interval elapsing between the closure of the driving circuits at the commutator segments 157 and 158, the C operator inserts plug 154 into jack 155, closing a circuit from grounded battery through a cut-off relay 165, the sleeve contacts of jack 155 and plug 154 and the winding of relay 151 to ground. Relay 151, upon energization, opens the circuit including lamp 152 and relay 150. Relay 150 opens the energizing circuit of relay 143, and this relay re-establishes the circuit for the relay 145. The C operator operates her ringing key 166, for signaling the called subscriber and this subscriber, by removing the receiver, operates in the well-known manner, a supervisory relay 167. Relay 167 establishes a circuit through its armature and front contact for relay 143, and this relay again opens the circuit of relay 145.

After the time interval of two seconds has elapsed, plate 158 closes a driving circuit through sequence switch contact 161, for moving sequence switch 112 into position 17. A circuit is now closed from ground, through the armature and back contact of relay 145, a sequence switch contact 162, a retardation coil 163, a sequence switch contact 164, trunk conductor 22, the lower brushes of selectors 11 and 10, a sequence switch contact 40, the winding of a supervisory relay 34, and the secondary winding of repeating coil 36, to grounded battery. Relay 34 becomes energized and closes a circuit from ground, through its armature and front contact, a contact 41 and the power magnet of sequence switch 19, to grounded battery, for driving this sequence switch out of position 14 into position 16. Lamp 32 is extinguished, indicating to the connecting operator that the C operator has taken care of the call.

65 When the subscriber at substation 110

restores his receiver to the switchhook, relay 167 becomes deenergized, and opens the circuit of relay 143, whereupon the above traced circuit, including relays 145 and 141, is established.

Upon the energization of relay 145, relay 34 becomes deenergized and closes a circuit from ground, through its armature and back contact, a sequence switch contact 41, and the lamp 33, to grounded battery, indicating to the connecting operator that disconnection is desired. If, at this time, the calling subscriber's disconnect signal (not shown) has also been actuated, the connecting operator removes plug 14 from jack 15, causing thus the deenergization of relays 16 and 17. Relay 16 closes through sequence switch contact 42, a driving circuit for sequence switch 19 and moves the same into position 1. The connecting operator also restores the sender, and the selectors 10 and 11.

As soon as sequence switch 19 is moved out of position 16, lamp 33 is extinguished and relay 130 becomes deenergized. A circuit is closed thereupon from ground, through the armature and back contact of relay 130, a contact 170 and the power magnet of sequence switch 112 to grounded battery, for moving this sequence switch out of position 17 into position 1, in which position, a circuit is closed from ground through the armature and front contact of relay 138, a sequence switch contact 137 and a lamp 172 to grounded battery. Seeing the lighting of lamp 172, the B operator removes plug 137 from jack 136, causing thus the deenergization of relays 145 and 141. Relay 141 upon deenergization, closes a circuit from ground, through its armature and back contact, the lower front contact and armature of relay 151, and lamp 152 to grounded battery. Seeing the lamp 152 lighted the second time, the C operator removes plug 154 from jack 155, opening thus the circuit of relays 165 and 151, whereupon lamp 152 is extinguished.

It will be seen from the above that by means of the interrupter plates 157 and 158, and the relay combination 141, 143 and 145, a simple and efficient means is provided for preventing the giving of a false disconnecting signal to the connecting operator in a system in which dry trunks interconnect two offices. In the absence of such delaying means, the supervisory relay 34 would be energized as soon as selector 11 seizes the trunk leading to plug 137, and would cause the moving of sequence switch 19 into position 16. Relay 34 would then be deenergized upon the first energization of relay 145 and the connecting operator would thus receive a false disconnecting signal, and would sever the connection before the C operator had time to complete it by inserting plug 154 into jack 155.

While the invention has been described

as embodied in a semi-automatic telephone system, it will be apparent to those skilled in the art, that it is applicable to signaling systems of widely varying character, such 5 as purely manual telephone systems, or systems in which not only the connecting, but also the B and C operators control selector switches for establishing connections.

What is claimed is:

- 10 1. In a telephone exchange system, a plurality of lines, means for interconnecting two of said lines, a signal for indicating the stage of operation of said means, a disconnect signal, switching mechanism for successively operating said signals, and means for delaying the operation of said mechanism after the actuation of the first mentioned signal for a definite interval.
- 15 2. In a telephone exchange system, a plurality of lines, a plurality of offices, means for establishing a connection between two of said lines through said offices, a signal operated upon the extension of said line from one office to the other, a disconnect signal 25 at one of said offices, means for actuating said disconnect signal after the operation of said first mentioned signal, and means at said other office for delaying the actuation of said disconnect signal for a definite interval.
- 30 3. In a telephone exchange system, a plurality of lines, two offices, means for establishing a connection between two of said lines through said offices, a dry trunk ex-

tending between said offices, a supervisory 35 relay at the first office, and means associated with the second office for delaying the operation of said relay for a definite interval.

4. In a telephone exchange system, a plurality of lines, a plurality of offices, means 40 for establishing a connection between two of said lines through said offices, a trunk for interconnecting two of said offices, means for supplying current to said trunk only during the establishment and the severing 45 of connections, supervisory means controllable over said trunk, and means for preventing the operation of said supervisory means during the establishment of the connection.

5. In a telephone exchange system, a plurality of lines, three offices, means for establishing a connection between two of said lines through said offices, a signal at the first office, a relay at the second office adapted to control said signal, a dry trunk interconnecting the second and third offices, said relay being connected to the trunk, means at the third office for connecting battery to said trunk only during the establishment and 60 severing of the connection, and means for rendering ineffective the operation of said relay during the establishment of the connection.

In witness whereof, I hereunto subscribe 65 my name this 24th day of May, A. D. 1916.

ALBEN E. LUNDELL.
